(57) **CLAIM**

The ornamental design for a toy tractor-trailer rig, as shown and described.

DESCRIPTION

FIG. 1 is a left elevation view of a toy tractor-trailer rig in accordance with our new design;

FIG. 2 is a right elevation view thereof;

FIG. 3 is a front elevation view thereof;

FIG. 4 is a rear elevation view thereof;

FIG. 5 is a top plan view thereof; and

FIG. 6 is a bottom plan view thereof;

FIG. 7 is a left elevation view of the tractor-trailer rig of FIG. 1, shown in its retail package configuration;

FIG. 8 is a right elevation view thereof;

FIG. 9 is a front elevation view thereof;

FIG. 10 is a rear elevation view thereof;

FIG. 11 is a top plan view thereof;

FIG. 12 is a bottom plan view thereof;

FIG. 13 is a left elevation view of the tractor-trailer rig of FIG. 1, shown in a decorated configuration;

FIG. 14 is a right elevation view thereof;

FIG. 15 is a front elevation view thereof;

FIG. 16 is a rear elevation view thereof;

FIG. 17 is a top plan view thereof; and,

FIG. 18 is a bottom plan view thereof.

The circular structures near the center of the top and bottom of the trailer in FIGS. 5, 11 and 12 are not parts of the design.
